CAN OPENER AND SEALER

Lawrence L. McLean, Butte, Mont.

Application October 14, 1949, Serial No. 121,422

1 Claim. (Cl. 30—6.1)

1. **1**

The present invention relates to a can opener and sealer and it consists in the combinations, constructions and arrangements of parts herein described and claimed.

Generally there is provided a can opener and sealer comprising a cover member adapted to fit over the upper end of a can and having a pair of transversely extending parallel guide members upwardly extending therefrom. Between the guide members and adjacent each end of the cover is an opening. A bar is provided with a pair of dependent projections one adjacent either end thereof and the bar is adapted to be received between the guide members. Projecting downwardly from each of the dependant portions of the bar is a penetrating member which is surrounded by a gasket of flexible material. The penetrating members are adapted to be inserted through the openings through the cover portion. The bar has centrally and loosely mounted therein a vertical pin which is adapted to be snugly received in the opening centrally provided in the cover. Pressure upon the bar will cause the penetrating members to puncture the can upon which the device is used and the gaskets act to seal the contents of the can against insects, dirt and the like when the can is not in use.

It is accordingly an object of the invention to provide a device of the character set forth which is simple in construction, inexpensive to manufacture and yet efficient and effective in use.

Another object of the invention is the provision of a device of the character set forth having novel means for opening fluid-containing cans.

Another object of the invention is the provision of a novel guide pin forming a part of the invention.

Another object of the invention is the provision of novel sealing means forming a part of the invention.

Other and further objects of the invention will become apparent from a reading of the following specification taken in conjunction with the drawings, in which

Figure 1 is a top plan view of an embodiment of the invention,

Figure 2 is a sectional view taken along line 2—2 of Figure 1,

Figure 3 is a sectional view taken along line 3—3 of Figure 1,

Figure 4 is a fragmentary sectional view taken along line 4—4 of Figure 2,

Figure 5 is a sectional view taken along line 5—5 of Figure 2,

2

Figure 6 is a bottom plan view of the device shown in Figure 1,

Figure 7 is a view similar to Figure 2 but showing the device immediately prior to its penetration into a can,

Figure 8 is a sectional view taken along line 8—8 of Figure 7,

Figure 9 is a fragmentary plan view of a cover forming a part of the invention, and

10 Figure 10 is a bottom plan view of a bar forming a part of the invention.

Referring more particularly to the drawings, there is shown therein a can opener and sealer comprising a circular cover 10 having a dependant 15 flange 11 which is adapted to snugly fit the sides of a can 12. Integrally formed with and upwardly extending from the cover 10 is a pair of parallel transverse guide members 13 between which and adjacent the outer ends thereof is provided a pair 20 of openings 14. A relatively small opening 15 is centrally provided in the cover 10 and lies between the guide members 13.

A punch bar 16 of generally rectangular shape when viewed from above, is adapted to be received 25 between the guide members 13 and has integrally formed therewith adjacent each of its ends a dependent portion 17 in each of which is embedded a penetrating member 18 surrounding which and affixed to the lower face of the portion 17 in each case is a gasket 19 formed of rubber or other resilient material.

A shoulder 20 is formed in each case between the portion 17 and the outer end adjacent thereto of the bar 16. Affixed to the underside of the cover 10 and immediately below the opening 15 is a spacing ring 21.

Centrally mounted in the bar 16 is a vertically extending pin 22 having an integrally formed head 23 at its upper end. The pin 22 is loosely 40 positioned in an opening 24 provided therefor and its lower end is adapted to be received in the opening 15 and to be held therein by frictional engagement with the sides thereof.

In operation, it will be apparent that when it 45 is desired to open a can 12, that the cover 10 is first placed thereon with its flange 11 enveloping the sides of the can. Thereupon the bar 16 is placed between the guides 13 and the pin 22 pressed downwardly by means of the head 23 to engage within the opening 15, whereupon the bar 16 may be successively administered a sharp blow at either end thereof to cause the successive penetration of the members 18 into the top 50 of the can 12. When the members 18 are pressed 55 downwardly into the top of the can, the gaskets

19 will come into contact therewith to effectively seal the contents of the can from insects, dirt and the like. It will be seen, however, that the device may easily be removed so that the contents of the can may be dispensed therefrom and that thereafter the device may be again set in position, the gaskets 19 meantime continuing to provide an effective sealing means therefor.

While but one form of the invention has been shown and described herein, it will be readily apparent to those skilled in the art that many minor modifications may be made herein without departing from the spirit of the invention or the scope of the appended claim.

What is claimed is:

A device of the character described comprising a cover having a pair of diametrically opposed openings each adjacent the periphery thereof and a centrally located relatively small opening, said cover having an integrally formed dependent flange for receiving the upper end of a can therein, a punch bar having a dependent portion adjacent each end thereof, and each receivable

in an opening in the cover, a penetrating member downwardly extending from each of the dependent portions, a vertically movable pin centrally disposed in said bar and frictionally and removably receivable in the relatively small opening in said cover, a resilient gasket affixed to the lower end of each of the dependent portions and surrounding its associated penetrating member, and a pair of upwardly extending parallel guide members formed in the upper side of said cover and slidably receiving said punch bar.
